(57) **CLAIM**

The ornamental design for a convertible bed and suitcase, as shown and described.

DESCRIPTION

FIG. 1 is a perspective view of the convertible bed and suitcase, shown in a closed configuration;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the convertible bed and suitcase, shown in a partially open configuration;

FIG. 9 is a perspective view of the convertible bed and suitcase, shown in an open configuration;

FIG. 10 is front elevational view thereof;

FIG. 11 is a rear elevational view thereof;

FIG. 12 is a right side elevational view thereof;

FIG. 13 is a left side elevational view thereof;

FIG. 14 is a top plan view thereof; and,

FIG. 15 is a bottom plan view thereof.

In the drawings, the broken lines depicting a handle wrap are showing portions of the article that form no part of the claimed design. In FIGS. 1-3 and 11, the broken lines on the exterior of the article, not associated with the handle wrap, depict stitching. In FIGS. 8-10, the broken lines on the interior of the article depict boundaries that form no part of the claimed design.

1 Claim, 13 Drawing Sheets
